LOCOMOTIVE STOKER

Charles J. Surdy, Tuckahoe, N. Y., assignor, by
mesne assignments, to The Standard Stoker
Company, Inc., New York, N. Y., a corporation
of Delaware

Application May 26, 1934, Serial No. 727,624

9 Claims. (Cl. 110—101)

My invention relates to stokers for locomotives and the like and it appertains particularly to improvements in the feeding of fuel to the distributing means as well as in the distributing means itself.

Specifically, my invention relates to stokers of the character shown in the United States Letters Patent No. 1,947,723 granted February 20, 1934, to Nathan M. Lower. Accordingly an object of my invention is to provide, in a stoker of the patented type, a modification wherein the fuel is urged over a plate member forming a separable bottom for the stoker discharge mouth and being separate also from the chambered jet member therebeneath, from which jet member the pressure fluid blasts are discharged for propelling the fuel into the firebox.

Another object of the invention contemplates extending the aforesaid plate member beyond and above the point of discharge of the pressure fluid blasts of the jet member; and still another object is the provision of such a plate member adjustably movable longitudinally of the conduit to vary its relative position with the point of discharge of the pressure fluid blasts.

A further object of my invention is the provision in the above described plate member of spaced fingers in the forward end thereof positioned at or forward of the point of discharge of the pressure fluid blasts to effect a separation of the fine from the coarse fuel. In carrying out this object I provide relatively low and high pressure propelling blasts acting respectively on the fine and coarse fuel.

Other objects reside in the provision of the particular means of shifting the plate member longitudinally of the stoker conduit, the attachment means for the jet member and the specific formation of the various parts and their coaction one with another as will become apparent from the following specification when read in connection with the accompanying drawings, in which,

Figure 1 is a fragmentary central vertical section through the rear portion of a locomotive with the stoker feed conduit in which my invention is embodied in similar section;

Figure 2 is a plan section taken on the line 2—2 of Figure 1;

Figures 3, 4 and 5 are sectional views taken on the line 3—3, line 4—4 and line 5—5, respectively, of Figure 1;

Figure 6 is a view of the structure shown in Figure 1 as seen from the interior of the locomotive firebox;

Figure 7 is a view similar to Figure 1, showing a modification; and

Figure 8 is a sectional view taken on the line 8—8 of Figure 7.

Throughout the description and claims the terms "forward" and "rearward" as applied to parts of the stoker are used relative to the direction of delivery of the fuel.

Referring now to Figures 1 to 6, inclusive, the boiler is shown at 10, its firebox at 11, and the backhead at 12 having a firing opening 13 therethrough. Fuel is delivered to the firebox by suitable stoker mechanism, only so much being shown as is necessary to a complete understanding of the invention. The stoker mechanism includes an inclined conduit 14 which leads forwardly from a source of fuel supply and is provided with a laterally flared discharge mouth 15 in communication with the firing opening 13 for delivering fuel thereto. Flanges 16 are provided at the side walls 17 of the discharge mouth 15 for securing the conduit 14 to the backhead 12.

The bottom wall 18 of the discharge mouth 15 is recessed as at 19, this recess preferably being wider at its forward end than at the rearward end thereof. The bottom wall 18 is disposed inwardly from each side wall 17 so that it forms a shelf 20 at each side wall. From the underside of each shelf 20 depends a flange 21 which extends longitudinally of the locomotive. These flanges 21 are spaced one at each side of the recess 19 and are disposed parallel to each other, forming a guide for the plate member 22, as will presently appear.

This plate member 22 comprises a relatively thin portion 23 which fits snugly between the flanges 21 at the undersides of the shelves 20 to form a floor for the recessed portion of the discharge mouth 15. Immediately beneath the thin portion of this plate member is a chambered jet member 24, the upper wall 25 of which forms a rest for the underside of the plate member 22. The chambered jet member 24 is secured between the flanges 21 by means of bolts 26 passing through the named flanges and engaging the chambered jet member. At its forward end, the jet member rests upon lugs 27 which project inwardly from the flanges 21. Thus the plate member 22 is mounted in grooves which are formed by the spaced parallel flanges 21, the inward projections 20a of the shelves 20 which define the recess 19, and also by the upper wall 25 of the jet member 24, the top surface of this upper wall being spaced below the under side of

the inward projections 20a as clearly shown in Figure 3.

The chambered jet member 24 is provided with a transverse front face 28 extending practically across the entire width of the discharge mouth 15 and preferably adjacent the outer surface of the backhead 12. Pressure fluid is supplied to the chambers such as 29, of which there are several, through intakes 30 which register with slots 31 in the flanges 21 to permit a pipe 32 to be threaded into each intake. Each pipe 32 leads from a source of pressure fluid and is usually provided with suitable valve means for the independent control of pressure.

15 Fuel is advanced through the conduit 14 by a conveyor screw 33, which preferably terminates adjacent the rearmost edge of the recess 19. The screw 33 urges fuel through the discharge mouth 15 along the upper surface of the plate member 22, the forward edge 34 of which extends a substantial distance forward of the front face 28 of the jet member and above the fuel receiving surface 35 of the distributor table 36. Within the mouth portion 15 are the independently operable 20 deflector vanes 37, one at each side of the stream of fuel, for diverting the fuel to various portions of the distributor table fuel receiving surface 35.

The forward portion of the plate member 22 is provided with a plurality of indentations 38, 25 which extend rearwardly from the forward edge 34 to form a plurality of fingers 39. Smaller particles and granules of fuel fall downwardly through the indentations 38 while the larger lumps pass over the fingers 39 and drop over the 30 edge 34 onto the fuel receiving surface 35 of the distributor table 36. Low pressure blasts of pressure fluid emanating from the lower jet openings 40 in the front face 28 sweep across the table 36. The jet openings 40 are drilled in the 35 front face 28 of the jet member 24 so that there is a jet opening for issuing a blast of pressure fluid beneath a respective indentation 38 in order to propel the smaller particles of fuel into the firebox. In a plane above the jet openings 40 are 40 the relatively larger jet openings 41 drilled in the front face 28 so that there is a jet opening 41 beneath a respective finger 39, and since the blasts issuing from these openings issue blasts of pressure fluid of greater volume or greater effective 45 pressure, they serve to project the larger lumps of fuel passing over the fingers 39.

Since the front face 28 of the chambered jet member 24 is adjacent the outer surface of the backhead 12, means are provided on the distributor table 36 for deflecting a portion of the fuel laterally toward the rear corners of the firebox. Accordingly, each forward side portion of the table 36 is provided with a channel 42 and a curved rib 43 for intercepting and laterally deflecting a portion of the fuel projected by the pressure fluid blasts. The distributor table 36 may be attached to the stoker conduit 14 by means of the bolts 44 engaging flanges 45, one at each side of the table.

60 Preferably, the plate member 22 is movable longitudinally of the conduit 14 to vary the height from which the fuel drops onto the table 36 and to adjust the position of the forward edge 34 with respect to the point of discharge of the pressure fluid jets emanating from the front face 28. For this purpose, the lower or rearward end of the plate member 22 is provided with an oblique slot 46 which is engaged by a pin 47. The upper portion of the pin 47 is provided with a 65 shoulder 48 while the lower portion engages a

block 49. The block 49 forms a bearing 50 for the shaft portion 51 of a threaded stem 52 which is screwed into a lug 53 carried by the conduit 14.

Whenever it is desired to move the plate member 22 longitudinally of the conduit, this can be done by turning the threaded stem 52 by means of the hand wheel 54, moving the block 49 and the pin 47 in a straight line, transversely with respect to the conduit 14. Inward movement of the stem 52 and the corresponding movement of the block 49 and the pin 47 will cause the plate member to be retracted from the firing opening 13, by reason of the engagement of the pin 47 with the oblique slot 46, while outward movement of the stem 52 and the corresponding movement of the aforesaid associated parts will move the plate member 22 forwardly and upwardly with respect to the jet face 28.

In the operation of the structure described, fuel is conveyed forwardly and upwardly in the conduit 14 by the screw 33 onto the plate member 22 over which it is advanced to the forward edge 34 where the fuel then falls between the fingers 39 or passes over them to drop a distance variable by adjustment of the plate member toward or onto the distributing table 36 at a point forward of the point of discharge of the pressure fluid jets issuing from the jet openings 40, 41. The pressure fluid jets act upon the falling fuel to propel it forwardly across the table 36 and cooperate with the channels 42 and the ribs 43 to spread the fuel over the firebed of the firebox. In falling toward the table 36, the fuel assumes a dispersed or diffused condition, tending to break up any globular or coherent formations, thus making possible the use of lower propelling jet pressures and insuring more even distribution of the fuel over the firebed. Preferably the fuel drops forward of the front face 28 of the jet member at a point where it will be acted upon by the spreading conical formation of the jets at the point of highest effective intensity. This also permits the use of lower jet pressures and has the further advantage of eliminating the possibility of plugging the jet openings 40 and 41 as sometimes happens when the fuel is placed on the distributing table immediately in front of them.

Adjustment of the plate member 22 is particularly advantageous in that the position of the forward edge of the plate member with respect to the table 36 and the point of discharge of the pressure fluid jets may be varied to meet all conditions of service. In the broader aspects of the invention, the plate member 22 constitutes a removable wear plate protecting the chambered jet member 24 against any abrasive action of the fuel.

In the modified form of my invention, illustrated in Figures 7 and 8, the conveyor screw 60 extends forwardly to a point beyond the rearmost edge of the recess 19, and it will be observed that a portion 61 of the final turn of the screw flight 62 may be of the same radius as the rearward flights, but does not bear upon the thin plate portion 23a of the plate member 22a. In this form of the invention, the forward portion of the plate member 22a is not provided with the fuel separating fingers and indentations of the preferred construction. It is also contemplated that the chambered jet member 24 may be carried by the conduit 14 or an equivalent bracket formation by means of a single bolt 63 passing through the flanges 21. In all other respects, this form of my invention is identical with the preferred form.

These and other modifications are considered to be within the spirit of my invention as defined in the appended claims.

I claim:

- 5 1. The combination in a furnace having a wall
with a firing opening therethrough, of a stoker
conduit outside the furnace for delivering fuel
thereto, said conduit including a discharge mouth
in communication with said firing opening, the
10 bottom of said discharge mouth being recessed
to provide an opening therein, a separate plate
member at the recessed portion of said discharge
mouth forming a closure for the opening therein,
said plate member being arranged for adjust-
15 able movement longitudinally of the stoker con-
duit, a pressure fluid jet member at the under-
side of said plate member, a distributor table at
said firing opening extending forwardly from
said jet member, said jet member being separate
20 from said plate member and arranged to issue
blasts of pressure fluid over said distributor table,
and means for urging fuel through said con-
duit and along said plate member onto said dis-
tributor table into the zone of action of the pres-
25 sure fluid blasts.

2. The combination in a furnace having a wall
with a firing opening therethrough, of a stoker
conduit outside the furnace for delivering fuel
thereto, said conduit including a discharge mouth
30 in communication with said firing opening, the
bottom of said discharge mouth being recessed
to provide an opening therein, a separate plate
member at the recessed portion of said discharge
mouth forming a closure for the opening therein,
35 said plate member being arranged for adjust-
able movement longitudinally of the stoker con-
duit, a pressure fluid jet member at the underside
of said plate member, said pressure fluid jet
member being detachably carried by said stoker
40 conduit, a distributor table at said firing open-
ing extending forwardly from said jet member,
said jet member being separate from said plate
member and arranged to issue blasts of pres-
sure fluid over said distributor table, and means
45 for urging fuel through said conduit and along
said plate member onto said distributor table into
the zone of action of the pressure fluid blasts.

3. The combination in a furnace having a wall
with a firing opening therethrough, of a stoker
50 conduit outside the furnace for delivering fuel
thereto, said conduit including a discharge mouth
in communication with said firing opening, the
bottom of said discharge mouth being recessed
to provide an opening therein, a separate plate
55 member at the recessed portion of said discharge
mouth forming a closure for the opening therein,
said plate member being arranged for adjustable
movement longitudinally of the stoker conduit, a
pressure fluid jet member at the underside of said
60 plate member, said jet member having a front
face provided with jet openings directed toward
the furnace, the forward edge of said plate mem-
ber extending beyond the front face of said jet
member, a distributor table at said firing open-
65 ing extending forwardly from said jet member,
said jet member being separate from said plate
member and arranged to issue blasts of pressure
fluid through the jet openings in its front face
over said distributor table, and means for urging
70 fuel through said conduit and along said plate
member, the fuel falling over the front edge of
said plate member in advance of the front face
of said jet member into the zone of action of the
pressure fluid blasts issuing therefrom.

75 4. The combination in a furnace having a wall
with a firing opening therethrough, of a stoker
bottom of said discharge mouth being recessed
to provide an opening therein, a separate plate
member at the recessed portion of said discharge
mouth forming a closure for the opening therein,
a pressure fluid jet member at the underside of
said plate member, said jet member having a front
face provided with jet openings for issuing blasts
of pressure fluid for projecting fuel toward
the furnace, such blasts of pressure fluid consti-
tuting the sole means for projecting fuel toward
the firebox, the plate member having a forward
portion extending beyond the front face of said
jet member and being provided in the aforesaid
portion with separated indentations forming a
plurality of fuel separating fingers, a distributor
table at said firing opening extending forwardly
from said jet member, said jet member being sep-
arate from said plate member and arranged to
issue blasts of pressure fluid through an upper
and a lower row of jet openings in its front face
over said distributor table, and means for urging
fuel through said conduit and along said plate
member, the smaller particles of fuel falling
through said indentations of said plate member
into the zone of action of the pressure fluid blasts
issuing from the lower row of jet openings and the
larger lumps falling over the fingers into the zone
of action of the pressure fluid blasts issuing from
the upper row of jet openings.

5. The combination in a furnace having a wall
with a firing opening therethrough, of a stoker
conduit outside the furnace for delivering fuel
thereto, said conduit including a discharge mouth
in communication with said firing opening, the
bottom of said discharge mouth being recessed
to provide an opening therein, a separate plate
member at the recessed portion of said discharge
mouth forming a closure for the opening therein,
a pressure fluid jet member at the underside of
said plate member, said jet member having a front
face provided with jet openings for issuing blasts
of pressure fluid for projecting fuel toward
the furnace, such blasts of pressure fluid consti-
tuting the sole means for projecting fuel toward
the firebox, the plate member having a forward
portion extending beyond the front face of said jet
member and being provided in the aforesaid portion
with separated indentations forming a plurality
of fuel separating fingers, a distributor table at
said firing opening extending forwardly from
said jet member, said jet member being separate
from said plate member and having a front face
provided with a plurality of jet openings directed
toward the furnace and including an upper and
a lower row of jet openings for issuing blasts of
pressure fluid over said distributor table, the jet
openings of the upper row arranged to issue blasts
of pressure fluid beneath said fingers, and the jet
openings of the lower row arranged to issue blasts
of pressure fluid beneath the indentations of said
plate member, and means for urging fuel through
said conduit and along said plate member, the
smaller particles of fuel falling through said inden-
tations of said plate member into the zone of action
of the pressure fluid blasts issuing from the lower
row of jet openings and the larger lumps falling
over the fingers into the zone of action of the
pressure fluid blasts issuing from the upper
row of jet openings.

6. The combination in a furnace having a wall
with a firing opening therethrough, of a stoker

conduit outside the furnace for delivering fuel thereto, said conduit including a discharge mouth in communication with said firing opening, the bottom of said discharge mouth being recessed 5 to provide an opening therein, a separate plate member at the recessed portion of said discharge mouth forming a closure for the opening therein, said plate member being arranged for adjustable movement longitudinally of the stoker conduit, 10 a pressure fluid jet member at the under side of said plate member, said jet member having a front face provided with jet openings for issuing blasts of pressure fluid for projecting fuel toward the furnace, the plate member having a forward 15 portion extending beyond the front face of said jet member and being provided in the aforesaid portion with separated indentations forming a plurality of fuel separating fingers, a distributor table at said firing opening extending forwardly 20 from said jet member, said jet member being separate from said plate member and arranged to issue blasts of pressure fluid through an upper and a lower row of jet openings in its front face over said distributor table, and means for urging fuel 25 through said conduit and along said plate member, the smaller particles of fuel falling through said indentations of said plate into the zone of action of the pressure fluid blasts issuing from the lower row of jet openings and the larger lumps 30 falling over the fingers into the zone of action of the pressure fluid blasts issuing from the upper row of jet openings.

7. The combination in a furnace having a wall with a firing opening therethrough, of a stoker 35 conduit outside the furnace for delivering fuel thereto, said conduit including a discharge mouth in communication with said firing opening, a chambered jet member adjacent the discharge mouth of said conduit, said jet member including a front face at the firing opening and having a plurality of jet openings directed toward the furnace for issuing blasts of pressure fluid, a distributor table at said firing opening extending forwardly from said jet member beneath the 40 pressure fluid blasts, and a plate member at the discharge mouth of said conduit forming a floor for the fuel at the outlet thereof and being adjustably movable fore and aft with respect to said conduit, said plate member having a portion extending forwardly beyond the front face of said jet member.

8. The combination in a furnace having a wall with a firing opening therethrough, of a stoker 45 conduit outside the furnace for delivering fuel thereto, said conduit including a discharge mouth in communication with said firing opening, a

chambered jet member adjacent the discharge mouth of said conduit, said jet member including a front face at the firing opening and having a plurality of jet openings directed toward the furnace for issuing blasts of pressure fluid, a distributor table at said firing opening extending forwardly from said jet member beneath the pressure fluid blasts, and a plate member at the discharge mouth of said conduit forming a floor for the fuel at the outlet thereof and including a portion extending forwardly beyond the front face of said jet member, said plate member being adjustably movable fore and aft with respect to said front face, said portion being provided with separating fingers, and means for urging fuel 10 through said conduit, the smaller particles of fuel falling through said indentations and the larger lumps falling over the forward edge of said fingers onto the distributor table in advance of the front face of said jet member. 15

9. The combination in a furnace having a wall with a firing opening therethrough, of a jet member at said firing opening, said jet member having a front face apertured to discharge pressure fluid blasts into the furnace, conveying means 20 for delivering fuel into the zone of action of the pressure fluid blasts issuing from said jet member, such pressure fluid blasts being the sole means for projecting fuel into the firebox, and a distributor table at said firing opening extending 25 forwardly from said jet member beneath the pressure fluid blasts, said conveying means including a plate member having a fuel supporting surface extending forwardly and upwardly toward the furnace to a point short of the forward 30 end of said distributor table and forward of and a substantial distance above the level of the uppermost edge of the front face of said jet member, said plate member being provided in the forward portion thereof with separated indentations forming a plurality of fuel separating fingers, said jet member being arranged to issue blasts of pressure fluid across said distributor table through an upper and a lower row of jet 35 openings in the front face of said jet member, and means for urging fuel through said conduit and along said fuel supporting surface, said jet openings and fuel separating fingers being so arranged that smaller particles of fuel will fall between said fingers into the zone of action of the 40 pressure fluid blasts issuing from the lower row of jet openings and the larger lumps will fall over the forward end of said fingers into the zone of action of the pressure fluid blasts issuing from the upper row of jet openings. 45

CHARLES J. SURDY. 50
